UNITED STATES PATENT OFFICE.

ADOLPH W. H. LENDERS AND HANS F. BAUER, OF CEDAR RAPIDS, IOWA.

MANUFACTURE OF CORN-OIL.

1,225,664.

Specification of Letters Patent.

Patented May 8, 1917.

No Drawing.

Application filed November 3, 1915. Serial No. 59,342.

To all whom it may concern:

Be it known that we, ADOLPH W. H. LENDERS and HANS F. BAUER, citizens of the United States, residing at Cedar Rapids, in the county of Linn and State of Iowa, have invented certain new and useful Improvements in the Manufacture of Corn-Oil, of which the following is a specification.

Our invention relates to the manufacture of corn oil, from germs which have been subjected to contact with an acid, sulfurous acid, for instance, during a previous step or steps in the treatment of the grain; and the invention has for its primary object to provide an improvement in the method of producing corn oil whereby it is possible to obtain a better grade of oil, particularly an oil lighter in color and containing a smaller percentage of free, fatty acid, than can be produced by methods heretofore used. Ordinary commercially produced corn oil frequently contains as high as six per cent. of free, fatty acid, developed largely in the drying process because of the presence of some of the acid used in steeping the grain and these organic acids are detrimental to the quality of the oil. The oil is also ordinarily discolored more or less, which is undesirable because the trade prefers the oil to be as light in color as possible.

The largest production of corn oil is as a by-product of the starch and glucose industry. According to the method of manufacture ordinarily followed, the grain is steeped in a weak solution of sulfurous acid for the purpose of softening it and removing certain extractive matters. After the kernels are softened they are broken in mills, freeing the germ which is the oil bearing portion of the kernel. The germ is separated from the starch bearing portions of the kernel by being floated off in separators which ordinarily contain a starch liquor having a density of seven to twelve degrees Baumé. The germ is then washed to free it from adhering starch particles and is thereafter dried, ground up, steamed and then pressed in hydraulic presses or expellers.

Sulfurous acid is used during the initial steps of the manufacture, the steeping, grinding, separating and washing operations, for the purpose of preventing fermentation and the formation of slime in the apparatus. The acid, however, has a detri-

mental effect upon the oil in the germ during the treatment thereof subsequent to separation from the kernel particularly during the drying process which is ordinarily accomplished through the agency of heat. The presence of sulfurous or other like acid promotes the formation of free fatty organic acids by causing a decomposition of the glycerids. It also brings about a discoloration of the oil through oxidation or other causes. The result is that, as stated, the ordinary commercially produced corn oil contains a considerable percentage of free fatty acids, and is rather dark in color. The free fatty acids affect the value of the oil when used in the arts, as well as when it is refined. In the first place, the presence of these free fatty acids, for instance, in the manufacture of soap, cuts down the yield of glycerin from the oil. In the second place, in the refining of corn oil, for the purpose of making it edible or usable in edible products, the refinery loss is proportioned to the quantity of free fatty acids present. The presence of considerable amounts of free fatty acids in the crude corn oil also imparts to the finished refined oil a peculiar flavor which is not desirable.

Our invention improves upon the methods of manufacture heretofore employed in this industry by neutralizing the acid in the germs before they are dried. For this purpose we use, ordinarily after or during the washing step, a solution of sodium carbonate, sodium hydrate, or other suitable neutralizing agent, the strength of which will depend, of course, upon the acidity of the germs.

By treating the germs in this way we have been able to obtain a crude oil which will not contain in excess of one-half per cent. of fatty acids and which will be exceptionally light in color.

The oil, when in the germ, contains ordinarily a small percentage of free fatty organic acid. This has to be eliminated before the oil is fit for use as a salad oil or in edible compounds, because if the oil contains any appreciable amount of free fatty acid, it will become rancid when exposed to the air, due to enzymic action. Besides neutralizing the inorganic acid, the sulfurous acid, for instance employed in the starch process, the treatment of the germ with the alkali kills the enzymes which are present in

great numbers in corn or other like vegetable matter and when the germ or other oil bearing matter is subsequently heated, operates to neutralize the free fatty acid originally the oil, or what may have been produced by previous treatment thereof of one kind or another. Our improvement, therefore, besides preventing the losses due to decomposition of the oil, into relatively 10 valueless fatty acid, and besides preventing discoloration, checks any tendency to rancidity or undesirable flavor due to such traces of free fatty acid as there may be in the oil by destroying the microorganisms responsible therefor.

We claim:

1. Improvement in the manufacture of corn oil from germs previously treated with an acid which consists in neutralizing the

acid before subjecting the germs to the drying and pressing operations.

2. Improvement in the manufacture of corn oil which comprises steeping the grain in an acid solution, removing the germ, treating the same with a neutralizing agent 25 and drying the germ and expressing the oil therefrom.

3. Improvement in the manufacture of corn oil which consists in steeping the grain in dilute sulfurous acid, breaking up the kernels and removing the germ, washing the germ in water containing an alkali in sufficient quantities to neutralize the acid remaining from the steeping process, subjecting the germs to heat to dry the same, and 30 expressing the oil therefrom.

ADOLPH W. H. LENDERS.
HANS F. BAUER.
